UNITED STATES PATENT OFFICE

121,409

DESIGN FOR A TWIN PANEL HAMPER

William Fein, New York, N. Y.

Application February 26, 1940, Serial No. 90,511

Term of patent 7 years

To all whom it may concern:

Be it known that I, William Fein, a citizen of the United States, residing at New York, in the county of Kings and State of New York, have invented a new, original, and ornamental Design for a Twin Panel Hamper, of which the following is a specification, reference being had to the accompanying drawing, forming a part thereof.

The drawing is a perspective view of a hamper showing my new design; the back of the hamper being plain and the side not shown being identical with the one illustrated.

I claim:

The ornamental design for a twin panel hamper, as shown and described.

WILLIAM FEIN.
